UNITED STATES PATENT OFFICE

LUTHER C. BALDWIN, OF PROVIDENCE, RHODE ISLAND, ASSIGNOR TO U. S. BOBBIN & SHUTTLE COMPANY, OF PROVIDENCE, RHODE ISLAND, A CORPORATION OF RHODE ISLAND

BOBBIN AND BOBBIN REENFORCING MEANS

Application filed August 5, 1929. Serial No. 383,765.

This invention pertains to bobbins and bobbin reenforcing means, and while herein for convenience illustrated as embodied in a wooden spinning bobbin, it is equally applicable to yarn supports such as bobbins, tubes, or the like of other materials, for example paper, indurated fiber, etc., and whether designed primarily for spinning or for other purposes.

As illustrated in the patent to Baldwin et al. No. 1,145,662, July 6, 1915, it has heretofore been proposed to provide a bobbin with a reenforce ferrule comprising inner and outer flanges engaging the inner and outer surfaces respectively of the bobbin, but I find that better results, both from the standpoint of durability and economy of material, can be obtained in accordance with my present invention wherein, while the inner flange of the ferrule is still retained, I substitute for the long flange, which in the old construction embraced the outer surface of the bobbin, a relatively short flange, concentric with the inner flange and which is seated in an annular groove in the end of the bobbin body. This new arrangement requires less material than the old, it furnishes adequate protection for the inner edge of the body where protection is most needed, and provides a ready means for securing the reenforce ferrule securely and permanently in place so that it can not come off of the bobbin body or turn relatively thereto.

In the accompanying drawing, wherein I have illustrated certain desirable embodiments of the invention by way of example:

Fig. 1 is a fragmentary side elevation, partly in section, illustrating a spinning bobbin provided with one desirable form of my improved reenforce bushing;

Fig. 2 is a bottom plan view of the bobbin of Fig. 1;

Fig. 3 is a view generally similar to Fig. 1 but showing a modified form of reenforce bushing;

Fig. 4 is a bottom plan view of the bobbin of Fig. 3;

Fig. 5 is a view similar to Fig. 3 but showing a further modified form of bushing;

Fig. 6 is a bottom plan view of the device shown in Fig. 5;

Fig. 7 is a fragmentary sectional view, to larger scale, illustrating certain steps in the preparation of the bobbin for the reception of my improved ferrule;

Fig. 8 is a vertical section showing the ferrule of Fig. 3 before application to the bobbin;

Fig. 9 is a vertical section illustrating a further form of ferrule;

Fig. 10 is a side elevation illustrating another form;

Fig. 11 is a side elevation illustrating still another form of ferrule;

Fig. 12 is a side elevation of a similar ferrule but with a slight modification; and

Fig. 13 is a side elevation of the ferrule shown in Figs. 5 and 6.

Referring to the drawing, the numeral 1 indicates a spinning bobbin of usual type and which may be made of wood or other suitable material and having the lower end or base portion 2 which is of larger diameter than the upper tapered body of the bobbin and which, as is usual, is substantially cylindrical and provided with the usual peripheral grooves. This bobbin is provided with an axial bore 3 which is of enlarged diameter at its lower end, and the lower end of the base 2 is furnished with one or more slots 4 for the reception of the driving dog or dogs of the spinning spindle.

In preparation for the application of my improved reenforce ferrule I provide an annular groove G, Fig. 7, in the lower end of the base 2 of the bobbin, such groove being concentric with the axis of the bobbin and intermediate the inner and outer surfaces of the base 2. At the inner side of this groove I preferably cut away the bobbin to provide a rabbeted surface S, and preferably but not necessarily I provide an annular recess R in the wall of the bore at a distance from the surface S substantially equal to the length of the inner flange of the ferrule. In accordance with one embodiment of my invention I provide a reenforce ferrule (Fig. 1) having a portion 5 which is adapted to seat against

the under surface S (Fig. 7) of the bobbin and which has the inner and outer flanges 6 and 7 which initially are substantially cylindrical and concentric. The inner flange 6 is 5 of such diameter as to enter the bore with a close or driving fit and of such axial length that when assembled with the bobbin, its upper edge 9 may be spun or otherwise turned inwardly into the recess R if such be provided, or if the recess be omitted, then the metal may be pressed into the wood sufficiently to make it secure. The outer flange 7 may be made shorter than the inner flange and is 10 adapted to seat with a driving fit in the annular groove G. In assembling the parts, the flanges 6 and 7 are first forced into the bore and groove G respectively and then a part or all of the upper edge 9 of the flange 6 is turned outwardly, thereby securely retaining the ferrule in position to prevent relative axial movement of the ferrule and bobbin. The frictional resistance of the flange 7 in the groove G may in most cases 15 be depended upon to prevent relative rotation of the parts. Preferably the ferrule is applied to the bobbin before the slots 4 are cut, and these are then suitably formed, as by a milling operation, which simultaneously cuts out portions of the metallic ferrule and 20 the body of the bobbin proper.

In Figs. 3, 4 and 8 I have illustrated a modified construction in which the upper edge of the inner flange 6^b is provided with teeth 10, while the outer flange 7^b is substantially 25 the same as that shown in Fig. 1. In this arrangement the teeth of the inner flange, when the parts are properly assembled, may remain substantially straight, being embedded in the shoulder 12 of the bobbin, or 30 they may bend outwardly upon striking the shoulder or be bent by a suitable tool, while the outer flange 7^b fits snugly, as above described, in the annular groove G in the end of the bobbin. If desired, and in order to 35 obtain still further resistance to separation or relative movement of the parts, I may strike inwardly small sections 13 of the ferrule, as shown in Figs. 3 and 5, so as to form 40 detents or teeth projecting radially outward 45 into the substance of the bobbin base.

As shown in Fig. 11, I may, if desired, provide the ferrule with an inner flange 6^c of the type shown in Fig. 1 and an outer flange 7^c whose surface, either inner or outer 50 or both, is roughened, as for example by providing it with longitudinal ribs or corrugations.

In the modification shown in Fig. 10 the ferrule has the inner and outer flanges 6^e and 60 7^e having teeth 16 and 17 respectively at their upper edges. In Fig. 12 I have illustrated a still further modification in which the ferrule is furnished with the inner flange 6^f having teeth 18 at its upper edge, while the outer flange 7^f has corrugations 19 similar to the

corrugations 14 of Fig. 11. In Fig. 13 a still further modification is shown wherein the inner flange 6^g has the teeth 20 at its upper end, while the outer flange 7^g has teeth at its upper edge and is also corrugated, as shown 70 at 21. This ferrule is assembled with the bobbin body as shown in Figs. 5 and 6 by driving the outer flange 7^g into the groove in the end of the bobbin so that its teeth bite into the bobbin at the bottom of the groove. The inner flange 6^g enters snugly in the bore 75 in the bobbin, and the teeth 20 at its upper end may then be spun outwardly into the recess R and become embedded in the bobbin, while the ribs or corrugations 21 become embedded in the walls of groove G.

All of the arrangements thus disclosed provide resistance in varying degree against separation or relative movement of the ferrule and the bobbin while at the same time furnishing proper protection for the inner edge of the bobbin and resisting splitting of the latter, while the ferrule thus produced requires much less material in its construction than the ferrule disclosed in the patent 80 above referred to.

While I have illustrated certain desirable modifications of the invention, I wish it to be understood that it is not necessarily limited thereby, but that equivalent arrangements may be substituted for those herein disclosed without departing from the invention.

I claim:

1. A bobbin having a longitudinal bore and an annular groove in its end, and a reinforce ferrule comprising concentric flanges one of which fits within the bore of the bobbin and the other of which is seated in the groove in the end of the bobbin, and means providing interengaging projections extending along the surface of at least one of said flanges substantially axially of the bobbin and between the latter and the last-mentioned flange to prevent relative rotation of the bobbin and ferrule.

2. A bobbin having a longitudinal bore and an annular groove in its end, and a reinforce ferrule comprising spaced concentric flanges, one of which fits into the bore of the bobbin and the other into said annular groove, one of said flanges comprising means engaging the bobbin to prevent relative endwise movement of the bobbin and ferrule, and the other of said flanges having peripheral corrugations to prevent relative rotation of the bobbin and ferrule.

3. A bobbin having an axial bore and an annular groove in its end, and a reenforce ferrule comprising inner and outer spaced concentric flanges, the inner flange fitting in the bore and the outer flange in the groove, the inner edge of the inner flange being turned outwardly into an annular recess in the inner surface of the bobbin, and the outer

flange being peripherally ribbed to prevent relative rotation of the bobbin and ferrule.

4. A bobbin having an axial bore and an annular groove in its end, and a reenforce 5 ferrule comprising spaced inner and outer concentric flanges, the inner flange fitting in the bore and having teeth at its inner end turned outwardly and embedded in the bobbin, the outer flange fitting in the groove and 10 having teeth at its inner end embedded in the bobbin, said outer flange also being corrugated and having a driving fit in said groove.

5. A reenforce ferrule for bobbins comprising radially spaced inner and outer 15 flanges, one of said flanges having a peripherally ribbed surface for engagement with the bobbin to prevent relative rotation between the ferrule and the bobbin.

20 6. A reenforce ferrule for bobbins comprising radially spaced inner and outer flanges, the inner flange being of greater axial length than the outer flange, and the outer flange having a peripherally ribbed 25 surface for engagement with the bobbin to prevent relative rotation between the ferrule and the bobbin.

Signed by me at Providence, Rhode Island this thirty-first day of July 1929.

30 LUTHER C. BALDWIN.
